UNITED STATES PATENT OFFICE.

CHESTER SNOW JENNINGS, OF BOSTON, MASSACHUSETTS, ASSIGNOR, BY MESNE ASSIGNMENTS, TO AMERICAN PNEUMATIC SERVICE COMPANY, OF BOSTON, MASSACHUSETTS, A CORPORATION OF DELAWARE.

PNEUMATIC-DESPATCH-TUBE APPARATUS.

1,130,518.

Specification of Letters Patent.

Patented Mar. 2, 1915.

Application filed June 27, 1907. Serial No. 381,028.

To all whom it may concern:

Be it known that I, CHESTER SNOW JENNINGS, a citizen of the United States, residing at Boston, in the county of Suffolk and State of Massachusetts, have invented certain new and useful Improvements in Pneumatic-Despatch-Tube Apparatus; and I do hereby declare the following to be a full, clear, and exact description of the invention, such as will enable others skilled in the art to which it appertains to make and use the same.

My invention relates to improvements in pneumatic despatch tube apparatus and particularly to those systems which comprise a single transmission tube through which the carrier can be despatched in either direction.

One of the principal objects of this invention is to control the power from either terminal of said tube in such a manner as to cause the blower or pump which is connected with one end of the tube to supply a current of air in the proper direction of the transmission of the carrier. This is preferably accomplished by means of an electrically operated pole changer or reversing switch controlled from either terminal and adapted to start, stop or reverse the direction of rotation of the motor driving the blower or pump and necessarily changing the direction of the current of air in the transmission tube.

Another object of this invention is to automatically stop the motor when the carrier has reached either terminal, thereby limiting the use of the power to the interval necessary for the proper transmission and delivery of the carrier.

These and other objects will be herein-after referred to.

In the accompanying drawings, which illustrate a construction embodying my invention: Figure 1 is a diagrammatic view of the apparatus showing electric-controlling mechanism; Fig. 2 is an enlarged sectional view of one of the circuit-breakers and the lock valve. Fig. 3 is a detail section taken on line III—III of Fig. 2.

A and B represent two stations connected by the transmission tube C which tube is normally open to the atmosphere at station A and closed at its opposite end by a valve D. The end of the tube or terminal at sta-

tion B is connected by a pipe C' with the blower E which is driven by an electric motor M through belt M'. The motor M is series wound and its circuit includes a normally open switch or pole changer P by means of which the motor M may be started in either direction or stopped.

R is an ordinary cutout switch connecting the motor circuit with the line wires L and L'.

The valve D is normally held closed by a spring D⁵ and is adapted to be locked closed, when a pressure which is greater than the atmosphere is generated and supplied to the tube C, by means of a lock lever D' pivoted at D⁴ and carrying a projection D³ on its outer end. Located in close proximity to the valve D is a casing F containing the magnets F' which are adapted to operate upon one end of the bell crank lever F² pivoted at F³ and which acts as an armature for the magnet, the other end of the lever F² carrying a latch F⁴ adapted when magnets F' are energized to engage the projection D³ when the lever D' is closed against the valve D to positively hold the said valve locked in closed position. A spring F⁵ is adapted to throw back the lever F² and release the lever D' when the magnets F' are deenergized. Located adjacent the stations A and B are the casings G in which are located the contacts G' and a normally closed circuit-breaker G² pivoted at G³ to the casing G. A trip G⁴ projects into the transmission tube C and is jointed at G⁵ so as to be operated by the carrier in transit in one direction only to open the circuit-breaker, that is, the trip G⁴ located nearest the station A will be operated to break the circuit only by the carrier traveling toward that station, while the trip G⁴ located nearest the station B will be operated only by the carrier traveling in the reverse direction. To this end the edge G⁶ of the trip may bear against a stop pin G⁷, when in its normal position, and when, as viewed in Figs. 2 and 3, pressure is exerted downwardly upon said trip, pin G⁷ will cause it to rock the part G² out of engagement with the lower extremities of the spring contacts G' and thereby break the circuit. A pole changer P having an extended arm P² is adapted to be operated by the magnets S and T to reverse the direc-

tion of rotation of the motor M. The pole changer P is normally held open by a spring P³. The magnets S and T are controlled respectively and operated from the terminals A and B by the push buttons a and b.

When the carrier is to be despatched from station A to station B the carrier is inserted into the tube C at station A and the button or switch a is closed by the operator energizing the magnet S and attracting the armature w on the extended arm P² of the pole changer P, causing the said changer to swing and engage the contacts N' and M² closing the motor circuit through line wire L', arm P, wires n² and m, motor M, and thence through a wire m', arm P' to line wire L, thereby starting the motor, and through blower E causing a vacuum or current of air to be established in the tube C, and causing the carrier to be transmitted from station A to station B.

The circuit through the magnet S with the button a closed is as follows:—from the battery Z through wire Z', buttons a, wires s, through magnet S, thence through wire Z² to battery Z. The arm P² has in the meantime engaged contacts p and p' closing a circuit as follows:—from the battery Z through wires Z', p², magnet S, wire s, contact p, arm P², contact p', wire f, magnets F', wire f', circuit breakers G² by way of wire g, thence back to the batteries through wires g' and Z'. The automatic closing of this switch permits the release of push button a by the operator at the same time retaining the magnet S energized and the pole changer P in the position hereinbefore described.

The carrier when nearing station B engages the tip G⁴ operating the circuit-breaker G² breaking the circuit and de-energizing magnet S, permitting the pole changer P to be thrown into normal or open position by the spring P³ as shown in Fig. 1, thereby stopping the motor M and blower E. The carrier now discharges through the valve D at station B. In despatching a carrier from station B to station A the operator opens the valve D and inserts a carrier into the tube C and pushes the lock-lever D' upward, at the same time closing the push-button b which energizes the magnets F', and operating the lever F² causing the latch F⁴ to engage the projection D³ of the lever D' and locking the valve D in closed position. The closing button b energizes the magnet T and throws the pole changer P in the opposite direction from that hereinbefore described, closing the motor circuit, and starting the motor M and blower E in the reverse direction causing a pressure greater than the atmosphere in the transmission tube C, and causing the carrier to be despatched toward the station A.

The circuit when the push-button b is

closed is as follows:—from the batteries Z, through wire Z², magnet T, wire b', push-button b, wires b⁴ and f, through magnets F', wire f', circuit-breakers G², by way of wire g, through a normally closed circuit-breaker in the upper casing G (this last circuit breaker not being shown in detail since it is substantially like the circuit breaker G² in the lower casing G) thence through wires g' and Z' to the batteries Z. At the same time a circuit is closed as follows: from the batteries Z, through wire Z², magnet T, wires b' and b², contact t', arm P², contact t, wires b³ and f, through magnets F', wire f', circuit-breakers G², by way of wire g, thence through the wires g' and Z' to the batteries Z. This circuit permits the release of the push-button b by the operator, at the same time retaining the magnet T energized, holding pole changer P in operating position. The carrier on approaching station A engages the trip G⁴ nearest that station, causing the circuit-breaker G² to operate to break the circuit, allowing the pole changer P to resume normal or open position by means of springs P³, stopping the motor M and the blower E. At the same time the magnets F' are de-energized releasing through latch F⁴ the lock-lever D', which drops to the position shown in Fig. 2, unlocking the valve D. The carrier now discharges through the open end of the tube C at station A.

Having thus described my invention and set forth a construction embodying the same, what I claim as new and desire to secure by Letters Patent of the United States, is:

1. In a pneumatic despatch tube apparatus, a single tube for the transmission of carriers in either direction, stations located at opposite ends of the tube, an air pump connected with said tube adjacent one of said stations, a motor for driving said pump, a motor controlling device, means located at one of said stations for controlling said motor controlling device to start the motor in one direction, means located at the other station for controlling said motor controlling device to start the motor in the opposite direction, and means for automatically stopping said motor upon the arrival of the carrier at one of said stations, said motor stopping means including a trip projecting into said tube and means co-acting with said trip for rendering a movement thereof, by a passing carrier, idle when said carrier is traveling in one direction and operative when the carrier is moving in an opposite direction.

2. In a pneumatic despatch tube apparatus, a tube for the transmission of carriers in either direction, said tube provided at an orifice thereof with a closure having a bias for normally closing said orifice, a latch for locking said closure in its closed position,

means for actuating said latch, an air pump, a motor for driving said pump, and means co-acting with said latch actuating means for starting said motor when said latch 5 actuating means are rendered operative to dispose said latch in its locking position.

3. In a pneumatic despatch tube apparatus, a tube for the transmission of carriers in either direction, stations located substantially at orifices of said tube, an air pump connected with said tube, connections leading from said pump to a point in said tube adjacent one of said stations, a motor for driving said pump, a controlling device for 10 said motor and pump, means, a controlling part of which is located at one of said stations, for causing said motor to drive said pump in one direction, means, a controlling part of which is located at another of said 15 stations, for causing said motor to drive said pump in an opposite direction, said motor controlling device comprising movable parts all of which are normally movable solely by said last two mentioned 20 means, said controlling parts located at said stations each having a bias for a determined position thereof and being respectively adapted to exercise control of said motor and pump in manner aforesaid only when 25 moved out of said position, said apparatus having provisions for causing said motor to continue to drive in whichever direction it has been started at least until the delivery 30 of the carrier being propelled by the air current through said tube resulting from such driving of the motor, said controlling parts being each free to return to their respective determined positions aforesaid, after being actuated, while leaving the motor and pump subject to said provisions. 35

4. In a pneumatic despatch tube apparatus, a tube for the transmission of carriers in either direction, said tube provided at an orifice thereof with a closure having a bias 40 for normally closing said orifice, a positively acting member for locking said closure in its closed position, means for actuating said positively acting member, an air pump, a motor for driving said pump, and 45 means co-acting with said actuating means for starting said motor when said positively 50

acting means is disposed in its locking position.

5. In a pneumatic despatch tube apparatus, a tube for the transmission of carriers 55 in either direction, said tube provided at an orifice thereof through which carriers emerge, with a closure having a bias for normally closing said orifice, a movable part adapted to retain said closure in its closed 60 position against pressure exerted in said tube tending to open said closure when a carrier is being transmitted through said tube away from said orifice, said part having a tendency for movement into a position 65 to free said closure, whereby the emergence of a carrier traveling toward said orifice may be substantially unimpeded, means for holding said part in engagement with said closure, and means for establishing a carrier 70 propelling current of air in either direction through said tube, said holding means being operative only when said last mentioned means is operative to establish said current of air in a direction to transmit a carrier 75 away from said orifice.

6. In a pneumatic despatch tube apparatus, a tube for the transmission of carriers in either direction, stations located substantially at orifices of said tube, an air 80 pump connected with said tube, connections leading from said pump to a point in said tube adjacent one of said stations, a motor for driving said pump, a controlling device for said motor and pump, means, a controlling 85 part of which is located at one of said stations, for setting said controlling device to cause said motor to drive the pump in one direction, means a controlling part of which is located at another of said stations, for 90 setting the same device to cause said motor to drive the pump in an opposite direction, said motor controlling device comprising movable parts all of which are normally movable solely by said last two mentioned 95 means.

In testimony whereof I affix my signature, in presence of two witnesses.
